THERMOSTAT

Edward H. Schultz, Buffalo, Minn.

Application November 16, 1948, Serial No. 60,241

1 Claim. (Cl. 236—34)

1

The invention relates to improvements in thermostats used in cooling systems of internal combustion engines and the primary object of the invention is to prevent the cooling liquid in a radiator from freezing in cold weather under the influence of the fan draft by permitting the liquid to circulate freely, when the motor is started, until the radiator is warmed up.

Another object of the invention is to interrupt the free flow of the cooling fluid through the cooling system when the radiator and the cooling fluid are heated by the running motor to a desired degree.

A further object of the invention is to permit the cooling liquid to flow freely through the cooling system when the motor and the cooling fluid are heated beyond a predetermined degree.

The invention consists in the details of construction and in the combination and arrangement of the several parts of my improved thermostat, whereby certain advantages are attained, as will be hereinafter more fully set forth.

In order that my invention may be better understood, I will now proceed to describe the same with reference to the accompanying drawings, wherein:

Figure 1 is a view partly in section and partly in elevation illustrating an embodiment of the invention for heating liquid within a radiator, the valve being shown in initial open position;

Figure 2 is a view similar to Figure 1 with the valve closed;

Figure 3 is also a view similar to Figure 1 but shows the valve in its outer open position; and

Figure 4 is a sectional view taken substantially on the line 4—4 of Figure 2.

The thermostat in accordance with the invention as herein embodied comprises a standard round thermostat body 10 shaped like a bellows. One end of said body is secured by soldering or the like to a circular end plate 11. At diametrically opposite places two arms 12 are formed on said end plate and extend at right angles thereto alongside of the body 10. On the other end of body 10 a second circular end plate 13 is mounted in any preferred suitable manner and a valve rod 14 is arranged coaxially on the end plate 13 and extends at right angles therefrom between the arms 12. A cross arm 15 extends between the arms 12 and is secured on them adjacent to the free ends thereof as indicated at 16. In the middle portion of the cross arm 15 a guide rod 14 extends through said guide ring 17.

An annular flange 18 is firmly mounted on the free end portions of the arms 12 as indicated

2

at 19 and on the inner edge of said flange a shallow ring flange 20 is formed and extends outwardly at a right angle thereto.

On the free end portion of the valve rod 14 a circular damper 21 is firmly mounted so that the valve rod and the damper are located coaxially with each other. On the circumferential edge of the damper 21 a shallow outwardly extending flange 22 is formed and the outside diameter of this flange is such that it fits slidably in the annular flange 20. The relative length of the thermostat body 10 and the valve rod 14 with respect to the length of the arms 12 is such, that the damper flange 22 will be located below the annular flange 18, when the bellows-like thermostat body 10 is entirely collapsed as shown in Figure 1, and that the damper 21 will be arranged above the shallow inner flange 20 of the annular flange 18, when the body 10 is entirely expanded.

The above described thermostat is mounted on a cylinder block in any desired conventional manner, for instance, as shown in the accompanying drawings. In this embodiment an angular pipe fitting 23 is provided on one of its end portions with an outwardly extending flange 24, which is adapted to be secured by means of bolts 25 to a cylinder block 26 so that the bore of the fitting 23 communicates with the outlet opening 27 of the cooling chamber 28 in the cylinder block 26.

The assembled thermostat is inserted into the pipe fitting 23 so that the body 10 is located inside of the fitting and the annular flange 18 rests against the free end of the pipe fitting and is secured to the fitting in any conventional manner, for instance by means of screws 29, so that the thermostat is arranged approximately coaxially in the fitting.

A flexible hose 30, preferably made from rubber, is forced onto the free end of the pipe fitting 23 and leads to the inlet of the radiator (not shown) and is secured in position in any conventional manner for instance by means of wire rings 31 held together by a bolt 32 extending through eyes 33 formed on the end portions of each ring 31.

When the motor is started on a cold day, the thermostat body 10 is entirely contracted and the opening in the shallow inner flange 20 is open, as shown in Figure 1, so that the cooling fluid will flow through the pipe fitting 23, through the thermostat and the hose 30 into the radiator until the liquid is heated to a degree sufficient to expand the thermostat body 10 enough to push the damper 21 into the inner flange 20 preventing free circulation of the cooling liquid, until it is heated to a degree sufficient to expand the ther-

mostat body 10 until the damper 21 is located above the annular flange 18 as shown in Figure 3 so that the cooling liquid can circulate freely.

When the damper 21 is in channel closing position and fluid should collect in the hose 30, it is 5 drained off through a small drain hole 34 provided in the damper 21.

In this manner the radiator pipes (not shown) are warmed enough before the flow of the cooling liquid is interrupted, to prevent freezing of the 10 liquid under the influence of the fan draft.

I claim:

In a temperature control for the liquid cooling systems of motor vehicles and the like, the combination of a pipe fitting of the system and a 15 thermostatic control valve, said control valve being comprised in an annular seat secured on an end of said fitting, an open frame supported by said seat within and centrally of the said end of the fitting, an expansible element mounted within said frame, a rod projecting centrally from said 20 expansible element toward said seat, and a valve element carried by said rod for cooperation with said seat, said valve element being normally un-

seated with respect to the near side of said seat when the liquid of said system is cold and adapted to be moved by said expansible element relatively to said seat to cut off the flow of the liquid therethrough when the liquid is heated to a predetermined temperature and to be moved by said expansible element relatively to the opposite side of said seat to restore the flow of the liquid when the predetermined temperature thereof is exceeded.

EDWARD H. SCHULTZ.
